UNITED STATES PATENT OFFICE.

GEORGES BINCHE, OF ANGOULEME, CLAUDE DUPUIS, OF IVRY, AND HENRI PRIGNOL, OF LYON, FRANCE.

TWO-STROKE-CYCLE EXPLOSION-MOTOR.

1,317,067.

Specification of Letters Patent. Patented Sept. 23, 1919.

Application filed January 15, 1917. Serial No. 142,548.

To all whom it may concern:

Be it known that we, **GEORGES BINCHE**, **CLAUDE DUPUIS**, and **HENRI PRIGNOL**, all citizens of the French Republic, residing at **Angouleme**, **Charente**, **Ivry**, **Seine**, and **Lyon**, **Rhone**, respectively, in France, have invented certain new and useful Improvements in Two-Stroke-Cycle Explosion-Motors, of which the following is a specification.

The motor forming the object of the invention is of the type known as a "two cycle motor" and is operated by gaseous or liquid volatile or non-volatile fuels such as 15 lighting gas, gases from gas producers or blast-furnaces, petrol, benzine, alcohol, naphthalene vapors, paraffin, shist oil, heavy oils, etc.

The characteristic features of this motor
20 are as follows:—

1. The admission of the mixture of air and liquid or gaseous fuel is effected at a volume and pressure regulatable as desired the mixture sucked in being then transferred under pressure into the explosion chamber during the final period of the exhaust of the burnt gases through the extremity opposite to the exhaust orifice and through openings arranged so as to completely expel the burnt gases without their being able to mix with the fresh carbureted gases introduced under pressure.

2. The arrangement of the explosion and expansion chamber between two pistons of which one inclosing the other operates also to produce the suction of the fresh charge of mixture into a fixed cylinder and also acts as a guide for the second piston of which it forms the cylinder; these two pistons moving in opposite directions. Each of these pistons is connected to the motor crank shaft by connecting rods and simultaneously transmit the energy produced by the explosion of the gaseous mixture to the crank shaft which is consequently balanced. These two pistons are also the sole movable parts of the distribution or valve gear.

3. Perfect and rapid scavenging of the burnt gases is assured and their mixture with the fresh carbureted gases prevented by the interposition between the burnt gases and carbureted gases of a layer of pure air introduced at suitable pressure into the explosion and expansion chamber, imme-

diately before the transfusion of the fresh 55 charge of carbureted air.

4. The introduction, transfusion and exhaust orifices are registered by the two pistons and the valves are actuated by the movement of these pistons without the assistance of any intermediate actuating member. 60

5. The motor can rotate in either direction by reason of the symmetry of its construction. At starting the engine it will 65 rotate in the direction imparted to it either by hand or by means of a suitable starter.

In the annexed drawings:—

Figure 1 is a vertical axial section of the motor at right angles to the motor shaft the 70 pistons being at half stroke.

Fig. 2 is a vertical axial section passing through the motor shaft the pistons being at the end of their stroke at the moment of exhaust and transfusion.

Fig. 3 is a part vertical section showing automatic admission valve mechanism.

Fig. 4 is a part vertical section of Fig. 1 showing a compensating piston for regulating the pressure of the carbureted gases before their introduction into the explosion and expansion chamber. 80

In these various figures the same reference letters indicate the same parts.

In Fig. 1 where the pistons are shown in the middle of their stroke, it is supposed that the direction of rotation of the motor shaft is such that the piston cylinder *a* is descending, the said piston cylinder being connected to the motor shaft *A* by the two rods *a*¹ *a*² the trunnions *a*² *a*² and the fly disks *B* *B* fixed to the two parts of said motor shaft *A*. The head of the piston cylinder is provided with packing segments which slide in the fixed cylinder *c* the movement of the piston cylinder producing the vacuum and sucking the carbureted gases at atmospheric pressure into the cylinder *c*. These gases are introduced through the pipe *e* and automatically lift the valve *d* which when there is no suction is maintained on its seat by a spring or the like. The suction is produced when the piston cylinder *a* descends.

At the same time the air which fills the 105 annular space r and retained by the valve p lifts the valves t and is driven into and compressed in the annular chamber s .

formed at the bottom of the piston head. During the descent of the piston cylinder *a* the piston *b* which moves within said piston cylinder *a* with slight friction, rises and 5 the gases in the chamber of the piston cylinder, that is to say, the explosion chamber are compressed. During this first quarter of a rotation there is evidently a loss of power which is made up by the starting device in the case of the first revolution, or by the energy stored in the disks 10 *B*, *B* during running. The piston *b* is connected to the motor shaft by the rod *b*¹ the trunnion *b*² and the crank arms or disks *B*¹ 15 *B*² which connect the crank trunnions *a*² and *b*².

At the end of the first quarter of a rotation ignition takes place as will be explained later on.

20 At the end of its stroke the piston cylinder *a* rises again and compresses the fresh gases in the upper part of the cylinder *c* these gases being admitted and retained by the automatic valve *d*.

25 The orifices *f* situated at the upper part of the piston cylinder *a* coincide with or uncover the recesses *g* in the wall of the cylinder *c* and thus establish communication for the gases compressed in the upper part 30 of the cylinder *c* with the explosion and expansion chamber comprised between the piston cylinder *a* and the piston *b* and this chamber is filled with fresh gases while the burnt and expanded gases from the previous charge pass out through the outlet *i*; after the second quarter rotation the pistons 35 occupy the position shown in Fig. 1 and continuing their movement take the position shown in Fig. 2.

40 In its rising stroke, the piston cylinder *a* has also sucked air into the annular space *r* through the valve *p*.

In the fourth quarter rotation the piston cylinder *a* descends, the orifices *f* are closed 45 and the carbureted gases present in the explosion chamber are compressed. At the commencement of the following revolution a fresh charge of gases is sucked into the upper part of the cylinder *c* and the air previously sucked into the annular space *r* and retained by the valve *p* is driven into the chamber *s* comprised in the head of the piston cylinder *a* in which it is retained by the valves *t* which it had previously lifted 50 to enter said chamber *s*.

One of the openings *f* coming opposite the sparking plug *h* at the moment when the compression reaches its maximum the ignition takes place.

60 The weights of the fly-disks *B*, *B* are calculated so that at this moment the pistons pass the dead point by reason of the speed acquired and they are driven by the expansion of the gases in opposite directions, 65 the piston *b* after the expansion of the gases

a little before it reaches the bottom of its downward stroke uncovers the exhaust ports *i* and the burnt gases are evacuated.

Also the piston cylinder *a* a little before reaching the end of its upward stroke brings 70 the orifices *f* opposite recesses *u* formed in the lateral wall of the cylinder *c* a little below the recesses *g* previously described, which puts the compressed air chamber *s* 75 into communication with the explosion and expansion chamber by means of the orifices *v* *f* as shown in Fig. 2.

This compressed air immediately expands and continues to drive out the burnt gases 80 and is thus interposed between these fresh gases and the burnt gases which latter are completely evacuated without being able to mix with the carbureted gases previously compressed in the upper part of the fixed 85 cylinder *c* when they are in their turn introduced into the explosion chamber by the orifices *f* which uncover the recesses *g* just before the piston cylinder *a* reaches the end 90 of its stroke and communication of the explosion chamber with the chamber *s* by the openings and recesses *u*, *v*, *f*, has been interrupted and which prevents the entrance of the carbureted gases into said chamber *s*.

The movement of rotation and the timing 95 continue in the order described.

The orifices *f* *g* *u* *v* are equal in number and arranged diametrically opposite each other so that the scavenging of the cylinder *a* is rapidly effected.

100 Since when passing the dead point the parts of the motor are perfectly symmetrical with respect to the vertical plane containing the axis of the motor shaft, and the movement of the parts is the same in either direction of rotation of the motor, it is evident that the motor is reversible and it is sufficient to start it in one direction or the other to maintain the rotation in such direction.

110 To stop the motor it is sufficient to cut off the fuel supply without closing the pipe *e* or switching off the ignition.

We have described the principal parts of the motor which is intended to be operated 115 by means of gaseous or sufficiently volatile fuels to form with air an explosive mixture; we would add the following remarks:

1. The relative sections of the piston *b* and cylinder *c* can be determined so that the 120 amount of expansion in different types of motors can vary. If for example these sections only differ slightly, by making the cylinder *c* slightly larger than piston *b*, the mass of carbureted gas forming a charge 125 would only occupy, at atmospheric pressure, a little more than half the maximum capacity of the explosion chamber. If however the section of cylinder *c* is increased without altering that of the piston *b* the 130

amount of expansion of the burnt gases can be diminished as much as required.

- The pressure at which the transfusion of the fresh carbureted gases into the explosion chamber reaches a value determined can be regulated. To reduce this pressure it is sufficient to lengthen the cylinder *c* without altering its diameter or the stroke of the pistons; to increase it, it is sufficient to reduce the residual space at the bottom of the cylinder *c* left by the piston cylinder *a* when it is at the bottom of its stroke. Different types of motors can thus be made in each of which the expansion of the burnt gases 15 is more or less extended in the explosion chamber, without having to alter the compression in the latter for a given length of piston stroke and a given section of the piston *b*. In other words in one type of motor 20 a charge of carbureted gas could be sucked in by means of the cylinder *c* which charge at atmospheric pressure would have the volume of the maximum capacity of the explosion chamber which would result in a 25 low expansion motor. In another type of motor a previous charge could be reduced to nearly half while maintaining the same compression for the transfusion of the charge it being sufficient for this to diminish 30 the section of the cylinder *c* without changing either the section of the piston *b* or the stroke of the pistons. We are thus able to admit by transfusion into the explosion chamber a charge of carbureted gas which 35 if it were measured at atmospheric pressure would have a volume either inferior or equal or even greater than the maximum capacity of said chamber while having at the same time sufficient expansion and high compression. The greater the expansion the less will be the loss of heat and energy at the 40 discharge of the burnt gases and consequently the power of the motor will be greater.
- 45 3. The explosion is produced in the chamber limited by the inner walls of the piston cylinder *a* and by the upper face of the piston *b*. The explosion of the carbureted mixture produces a quantity of heat proportional to the quantity of fuel contained 50 in the charge since oxygen is present always in quantity more than sufficient to assure complete combustion if the amount of fuel is correctly proportioned. Part of this heat 55 passes into the atmosphere; this loss of heat exists in all thermic motors and in explosion or internal combustion motors, it is reduced proportionately as the expansion of the burnt gases is prolonged. Another 60 part of the combustion heat is immediately transformed into mechanical work by the expansion of the burnt gases and this quantity of heat utilized is so much greater as the expansion of the gases is more complete.
- 65 65 The remainder of the heat produced heats
- the walls of the explosion chamber. Owing to the situation of this chamber the cooling of its walls is not effected by a water jacket or by radiator plates; the said walls heating, on the one hand, the fresh air sucked 70 into the chamber *r*, and, on the other hand, the charge of carbureted air sucked into the upper part of the cylinder *c*. The lateral lower walls of the cylinder *c* and the cylindrical member *E*² guiding the piston 75 cylinder *a* are alone cooled by the direct action of exterior means (radiator plates or a water jacket). Consequently in the improved motor there is recuperation of the heat transmitted by the burnt gases to the 80 walls of the explosion chamber which increases the efficiency of the motor.
4. The method of construction suppresses all anfractuosity capable of producing eddies and of forming obstacles to the movement of the gases after ignition and during the expansion.
5. The two pistons *a* and *b* being keyed at 180° during the expansion, the piston cylinder *a* acts by traction on the trunnions 90 *a*² *a*² and the piston *b* acts by pressure on the trunnion *b*² of the crank; these opposite forces determine the rotation of the principal shaft without causing an important reaction on the bearings, the longitudinal 95 components of the forces transmitted by the coupling rods being balanced.
- Any suitable means of connection can be used between the motor cylinders and the bearings of the main shaft A. In the construction illustrated this connection is effected by means of a casing *a*³ inclosing the connecting rods and cranks.
- Also any means can be used for cooling the cylinder *c* for instance radiator disks 100 or as shown in the drawing a water jacket *E* surrounding the lateral wall of the cylinder *c*, the bottom *E*¹ thereof and the guide *E*².
- The water enters by the lower orifice *w* 110 and passes out through the upper orifice *w*¹. The piston cylinder *a* is cooled along part of its length by conduction from points where it is in contact with the inner wall of the water jacket; further the piston cylinder is cooled to a certain extent by the action of the carbureted gases sucked through the valve *d* and the air introduced into the chamber *r* by the valve *p*. This method of cooling has been found in practice sufficient for proper operation of the 115 motor.
- In Fig. 3 a modification of the distribution mechanism is illustrated which as in the previous construction is operated by the 120 displacement of the piston cylinder *a*. The orifices *f* act as before described to put the chamber *s* into communication with the top of the piston cylinder *a* at the proper moment by means of the recesses *u* and the ori- 125
- 130

fices *v* so as to introduce the fresh air which comes between the burnt gases and a fresh charge of carbureted air during the scavenging of the burnt gases and also to put the explosion chamber into relation with the ignition device. In this modification the recesses *g* are dispensed with and the introduction of the carbureted gases is effected by the valves *j* and *k*, the piston *a* in its 10 down stroke tending to form a vacuum in the upper part of the cylinder *c*. Owing to the atmospheric pressure the valve *j* balanced by the spring *x* allows the quantity of carbureted air necessary to fill the cylinder *c* to pass therein. The spring *y* keeps the valve *k* closed. After the explosion has taken place the piston *a* reascends. The carbureted gases previously admitted are compressed in the upper part of the cylinder *c*. A little before the piston *a* reaches 20 the top of its stroke the rod of the valve *k* meets the adjustable abutment *z* directly after the air compressed in the chamber *s* has expelled the burnt gases; the valve *k* 25 then opens and the transfusion of the charge of carbureted air into the explosion chamber is effected, without it being able to mingle with the burnt gases which are separated from this charge by the air coming 30 out of the chamber *s*.

Apart from this slight difference the working of the motor is the same as in the case of Figs. 1 and 2, the various cycles previously described continue periodically 35 in the order indicated.

Fig. 4 shows another modification for the purpose of regulating the pressure at which the carbureted gases from the upper part of the cylinder *c* are transfused into the 40 explosion chamber. This device works as follows:

In its down stroke the piston-cylinder *a* forces a charge of carbureted gas into the upper part of the cylinder *c*. During this 45 action the piston *l* driven by the spring *m* is at its lower position. The piston-cylinder *a* reascending, the automatic valve *d* is closed again and the charge of carbureted air compressed by the head of the piston *s* 50 acts on the piston *l* and raises it a little before the limit of compression which is not to be exceeded is attained, and in such a manner that this maximum compression is reached at the moment when communication 55 is established by the recesses *g* and the orifices *f* between the cylinder *c* and the explosion chamber; this is effected by giving the spring *m* the proper dimensions and strength. While the compensating piston 60 is rising the space occupied by the charge is increased to the extent of displacement of the aforesaid piston *l* and the compression of the charge is thus limited. As soon as 65 communication is established between the cylinder *c* and the explosion chamber by

the recesses *g* and the orifices *f* the charge of carbureted air expands, its pressure decreases and the compensating piston *l* driven back by the spring *m* returns to its lower position before the communication with the 70 explosion chamber is again closed, so that the charge in the cylinder *c* is transfused into said chamber.

What we claim as our invention and desire to secure by Letters Patent of the United 75 States is:—

1. In a motor of the character described the combination of a fixed cylinder having a part of reduced diameter and provided with two series of circumferentially disposed 80 recesses in its part of larger diameter for establishing communication between the cylinder and the explosion chamber at different times, means for introducing the explosive mixture into said fixed cylinder, a valve controlling said admission, a piston cylinder sliding in the part of smaller diameter of the fixed cylinder and having an enlarged head provided with an annular chamber and ports adapted to coincide with one series of 85 said recesses and sliding in the part of the fixed cylinder of larger diameter so that an annular space is formed between the part of small diameter of the piston-cylinder and the part of larger diameter of the fixed cylinder 90 during the movement of the piston-cylinder, a valve in said fixed cylinder for admitting air to said annular space, valves in the head of the piston cylinder allowing the air compressed in said annular space 100 by the downward movement of the piston-cylinder head to pass into the annular chamber in said head, a piston movable within said piston-cylinder and in reverse directions to the movement of said piston-cylinder 105 means connecting said piston cylinder to said motor shaft, means for igniting the explosive mixture, means for evacuating the burnt gases from the motor and means for transferring the compressed air in the annular chamber in the piston head into the space comprised between said piston cylinder and piston between the burnt gases passing out from said space and the fresh mixture flowing therein and means for cooling 110 the motor.

2. In a motor of the character described the combination of a fixed cylinder having a part of reduced diameter and provided with a series of circumferentially disposed 115 recesses in its part of larger diameter, means for introducing the explosive mixture into said fixed cylinder, a valve in the head of said fixed cylinder controlling said admission, a piston cylinder sliding in the part of smaller 120 diameter of the fixed cylinder and having an enlarged head provided with an annular chamber and ports adapted to coincide with said recesses and sliding in the part of the fixed cylinder of larger diameter so that an 125

annular space is formed between the part of small diameter of the piston-cylinder and the part of larger diameter of the fixed cylinder during the movement of the piston cylinder, 5 a valve in the head of said piston cylinder admitting the mixture therein a valve in said fixed cylinder for admitting air to said annular space, valves in the head of the piston-cylinder allowing the air compressed 10 in said annular space by the downward movement of the piston-cylinder head to pass into the annular chamber in said head, a piston movable within said piston-cylinder and in reverse directions to the movement of said piston-cylinder means connecting said piston to the motor shaft, means connecting said piston cylinder to said motor shaft, means for igniting the explosive mixture, means for evacuating the burnt 15 gases from the motor and means for transferring the compressed air in the annular chamber in the piston head into the space comprised between said piston cylinder and piston between the burnt gases passing out 20 from said space and the fresh mixture flowing therein and means for cooling the motor. 25 3. In a motor of the character described the combination of a fixed cylinder having a part of reduced diameter and provided 30 with two series of circumferentially disposed recesses in its part of larger diameter, means for introducing the explosive mixture

into said fixed cylinder, a valve in the head of said fixed cylinder controlling said admission, a piston cylinder sliding in the part 35 of smaller diameter of the fixed cylinder and having an enlarged head provided with an annular chamber and ports adapted to coincide with said recesses and sliding in the part of the fixed cylinder of larger diameter, 40 an air admission valve in said fixed cylinder, valves in the head of the piston cylinder for controlling the admission of air into the annular chamber, a piston movable within said piston-cylinder and in reverse directions 45 to the movement of said piston-cylinder means connecting said piston to the motor shaft, means connecting said piston cylinder to said motor shaft, means for igniting the explosive mixture, means for evacuating 50 the burnt gases from the motor, means for cooling the motor, a cushioning piston in the head of said fixed cylinder and a spring governing the movement of said cushioning piston. 55

In witness whereof we have signed this specification in the presence of two witnesses.
